BACKGROUND OF THE INVENTION

The present invention relates to a new and distinct cultivar of *Hydrangea* plant, botanically known as *Hydrangea paniculata*, commercially referred to as a Hardy or Panicked *Hydrangea* and hereinafter referred to by the name 'LC NOS'.

The new *Hydrangea* plant is a product of a planned breeding program conducted by the Inventor in Boskoop, The Netherlands. The objective of the breeding program is to create new *Hydrangea* plants with uniform plant habit and attractive inflorescences.

The new *Hydrangea* plant originated from an open-pollination in July, 2013 in Boskoop, The Netherlands, of *Hydrangea paniculata* 'Limelight', disclosed in U.S. Plant

(57) **ABSTRACT**

A new and distinct cultivar of *Hydrangea* plant named 'LC NOS', characterized by its medium in size and broadly upright plant habit; moderately freely branching habit with strong lateral branches; freely flowering habit with plants remaining in flower for a long period time; dense and hardy inflorescences with light yellow green to white-colored sterile flowers that age attractively to red in color with development; and good garden performance.

2 Drawing Sheets

2

Pat. No. 12,874, as the female, or seed, parent with an unknown selection of *Hydrangea paniculata* as the male, or pollen, parent. The new *Hydrangea* plant was discovered and selected by the Inventor as a single flowering plant from 5 within the progeny of the stated open-pollination in a controlled greenhouse environment in Boskoop, The Netherlands during the summer of 2016.

Asexual reproduction of the new *Hydrangea* plant by 10 vegetative tip cuttings in a controlled environment in Boskoop, The Netherlands since the summer of 2016 has shown that the unique features of this new *Hydrangea* plant are stable and reproduced true to type in successive generations.

SUMMARY OF THE INVENTION

Plants of the new *Hydrangea* have not been observed under all possible combinations of environmental conditions and cultural practices. The phenotype may vary somewhat with variations in environmental conditions such as temperature and light intensity without, however, any variance in genotype.

The following traits have been repeatedly observed and 15 are determined to be the unique characteristics of 'LC NOS'. These characteristics in combination distinguish 'LC NOS' as a new and distinct *Hydrangea* plant:

1. Medium in size and broadly upright plant habit.
2. Moderately freely branching habit with strong lateral branches.
3. Freely flowering habit with plants remaining in flower for a long period time.
4. Dense and hardy inflorescences with light yellow green to white-colored sterile flowers that age attractively to red in color with development.
5. Good garden performance.

Plants of the new *Hydrangea* can be compared to plants of the female parent, 'Limelight'. Plants of the new *Hydrangea* differ primarily from plants of 'Limelight' in the following characteristics:

1. Plants of the new *Hydrangea* are more compact than plants of 'Limelight'.
2. Plants of the new *Hydrangea* and 'Limelight' differ in sterile flower color as sterile flowers of plants of the new *Hydrangea* are light yellow green to white in color whereas sterile flowers of plants of 'Limelight' are light green in color.

Plants of the new *Hydrangea* can be compared to plants of the *Hydrangea paniculata* 'LC NO2', disclosed in a U.S. Plant Patent application filed concurrently. In side-by-side comparisons, plants of the new *Hydrangea* differ primarily from plants of 'LC NO2' in plant habit as plants of the new *Hydrangea* are shorter and narrower than plants of 'LC NO2'.

Plants of the new *Hydrangea* can be compared to plants of the *Hydrangea paniculata* 'LC NO7', disclosed in a U.S. Plant Patent application filed concurrently. In side-by-side comparisons, plants of the new *Hydrangea* differ primarily from plants of 'LC NO7' in plant habit as plants of the new *Hydrangea* are shorter and narrower than plants of 'LC NO7'. In addition, plants of the new *Hydrangea* are not as freely branching as plants of 'LC NO7'.

Plants of the new *Hydrangea* can also be compared to plants of the *Hydrangea paniculata* 'Silver Dollar', not patented. In side-by-side comparisons, plants of the new *Hydrangea* differ primarily from plants of 'Silver Dollar' in the following characteristics:

1. Plants of the new *Hydrangea* are more compact than plants of 'Silver Dollar'.
2. Plants of the new *Hydrangea* and 'Silver Dollar' differ in sterile flower color as sterile flowers of plants of the new *Hydrangea* light yellow green to white in color whereas sterile flowers of plants of 'Silver Dollar' are white in color.

BRIEF DESCRIPTION OF THE PHOTOGRAPHS

The accompanying colored photographs illustrate the unique appearance of the new *Hydrangea* plant showing the colors as true as it is reasonably possible to obtain in colored reproductions of this type. Colors in the photographs may differ from the color values cited in the detailed botanical description which accurately describe the colors of the new *Hydrangea* plant.

The photograph on the first sheet (FIG. 1 of 2) is a side perspective view of a typical flowering plant of 'LC NO5'.

The photograph on the second sheet (FIG. 2 of 2) is a close-up view of a typical inflorescence of 'LC NO5'.

DETAILED BOTANICAL DESCRIPTION

Plants used in the aforementioned photographs and in the following description were grown during the late summer in 15-cm containers in an outdoor nursery in Boskoop, The Netherlands and under cultural practices typical of commercial *Hydrangea* production. During the production of the plants, day temperatures ranged from about 16° C. to 25° C. and night temperatures ranged from about averaged 5° C. to 16° C. Plants of the new *Hydrangea* were pinched one time and were two years old when the photographs and description were taken. As a Hardy or Priced *Hydrangea*, plants of the new *Hydrangea* are typically not treated with alum-

num sulfate to "blue" the inflorescences. In the following description, color references are made to The Royal Horticultural Society Colour Chart, 2015 Edition, except where general terms of ordinary dictionary significance are used.

Botanical description: *Hydrangea paniculata* 'LC NO5'.

Parentage:

Female, or seed, parent.—*Hydrangea paniculata* 'Limelight', disclosed in U.S. Plant Pat. No. 12,874.

Male, or pollen, parent.—Unknown selection of *Hydrangea paniculata*, not patented.

Propagation:

Type cutting.—By vegetative tip cuttings.

Time to initiate roots, summer.—About 20 days at temperatures about 16° C. to 30° C.

Time to produce a rooted young plant, summer.—About 50 days at temperatures about 16° C. to 30° C.

Root description.—Medium in thickness, fibrous; typically light brown in color, actual color of the roots is dependent on substrate composition, water quality, fertilizer type and formulation, substrate temperature and physiological age of roots.

Rooting habit.—Freely branching; dense.

Plant description:

Plant and growth habit.—Medium-sized, broadly upright plant habit; overall plant shape, obovate; strong and sturdy stems; moderately vigorous to vigorous growth habit and moderate growth rate.

Plant height.—About 50 cm to 60 cm.

Plant diameter or area of spread.—About 30 to 40 cm.

Lateral branch description:

Branching habit.—About three to seven lateral branches develop per plant; pinching will enhance lateral branch development.

Length.—About 30 cm to 50 cm.

Diameter.—About 6 mm.

Internode length.—About 2.5 cm to 10 cm.

Texture.—When developing, sparsely pubescent; fully developed, woody.

Aspect.—Upright to about 30° from vertical.

Strength.—Strong, sturdy; flexible.

Color.—When developing: Close to 145C. Developed: Close to 59B becoming closer to 166A with development; when woody, close to 199D.

Lenticels.—Density: Medium density to dense. Size: About 1.5 mm by 0.75 mm. Color, developing and developed stems: Close to 199D.

Leaf description:

Arrangement.—Opposite, simple.

Length.—About 10 cm.

Width.—About 5.5 cm.

Shape.—Elliptic to ovate.

Apex.—Acute.

Base.—Cuneate to obtuse.

Margin.—Serrate.

Texture, upper surface.—Sparsely pubescent; venation, densely pubescent; not rugose.

Texture, lower surface.—Sparsely pubescent; venation, densely pubescent; rugose.

Venation pattern.—Pinnate.

Color.—Developing leaves, upper and lower surfaces: Close to 144B. Fully developed leaves, upper surface: Close to 146A; venation, close to 146B. Fully developed leaves, lower surface: Close to 146B; venation, close to 147D.

Petioles.—Length: About 1.5 cm. Diameter: About 4 mm. Texture, upper and lower surfaces: Sparsely pubescent. Color, upper surface: Close to 59B. Color, lower surface: Close to 59C; proximally, close to 143C.

5

Flower description:

Flower type and habit.—Showy sterile flowers and small inconspicuous fertile flowers arranged on terminal panicles; panicles broadly ovate in shape; sterile flowers face upright to outwardly and slightly drooping depending on their position in the inflorescence; fertile flowers face mostly upright.

10

Fragrance.—None detected.

Natural flowering season.—Flowering begins in the midsummer and is continuous until late summer in Northern Europe.

15

Flower longevity.—Sterile flowers last about two months on the plant, sterile flowers persistent; fertile flowers last about five to seven days on the plant, fertile flowers not persistent.

20

Quantity of flowers.—Freely flowering habit; about 400 to 600 sterile flowers and about 20 to 40 fertile flowers per panicle.

Panicle height.—About 20 cm to 25 cm.

25

Panicle diameter.—About 15 cm to 20 cm.

Sterile flower buds.—Length: About 4 mm. Diameter: About 3 mm. Shape: Orbicular. Color: Close to 144C; towards the apex, close to 65C.

30

Fertile flower buds.—Length: About 3 mm. Diameter: About 4 mm. Shape: Obovate. Color: Close to 145C.

Sterile flower diameter.—About 5 cm.

Sterile flower depth (height).—About 5 cm.

Fertile flower diameter.—About 4 mm by 8 mm.

Fertile flower depth (height).—About 3 mm.

Petals, sterile flowers.—Quantity and arrangement: Four in a single whorl. Length: About 3 mm. Width: About 2 mm. Shape: Broadly lanceolate. Apex: Acute. Base: Obtuse. Margin: Entire. Texture and luster, upper and lower surfaces: Smooth, glabrous; matte. Color: When opening, upper and lower surfaces: Close to 150D. Fully opened, upper and lower surfaces: Close to NN155A; color does not change with development.

35

Petals, fertile flowers.—Quantity and arrangement: Five in a single whorl. Length: About 2 mm. Width: About 3 mm. Shape: Deltoid. Apex: Acute to subacute. Base: Obtuse. Margin: Entire. Texture and luster, upper and lower surfaces: Smooth, glabrous; slightly glossy. Color: When opening and fully opened, upper surface: Close to 157C; color does not change with development. When opening and fully opened, lower surface: Close to 157C; color does not change with development.

45

Sepals, sterile flowers.—Quantity and arrangement: Typically four, rarely five, in a single whorl. Length: About 2.5 cm. Width: About 2.5 cm. Shape: Elliptic to suborbicular. Apex: Obtuse to occasionally emarginate. Base: Obtuse. Margin: Entire. Texture and luster, upper and lower surfaces: Smooth, glabrous;

50

Garden performance: Plants of the new *Hydrangea* have been observed have good garden performance and to be suitable for USDA Hardiness Zones 5 through 9.

It is claimed:

1. A new and distinct *Hydrangea* plant named 'LC NO5' as illustrated and described.

* * * * *

matte. Color: When opening, upper and lower surfaces: Close to 150D. Fully opened, upper surface: Close to NN155A; color becoming closer to 144C and towards the margins, close to 53B with subsequent development. Fully opened, lower surface: Close to NN155B; color becoming closer to 144C and 53C with subsequent development.

Sepals, fertile flowers.—Quantity and arrangement: Four in a single whorl. Length: About 4 mm. Width: About 3 mm. Shape: Ovate. Apex: Acute. Base: Cuneate. Margin: Entire. Texture and luster, upper and lower surfaces: Smooth, glabrous; matte. Color: When opening and fully opened, upper surface: Close to NN155A; color does not change with development. When opening and fully opened, lower surface: Close to NN155A; color does not change with development.

Pedicels, sterile flowers.—Length: About 1.7 cm to 2.3 cm. Diameter: About 1 mm. Strength: Moderately strong. Aspect: About 30° from branch axis. Texture and luster: Sparsely pubescent; matte. Color: Close to 155A.

Pedicels, fertile flowers.—Length: About 3 mm to 5 mm. Diameter: About 1 mm. Strength: Moderately strong. Aspect: Mostly erect. Texture and luster: Sparsely pubescent; matte. Color: Close to NN155A.

Reproductive organs, sterile flowers.—Stamens: Quantity per flower: About eight or nine. Filament length: About 2 mm to 4 mm. Filament color: Close to 155A. Anther length: About 1 mm. Anther shape: Orbicular or parted. Anther color: Close to 155C. Pollen amount: Abundant. Pollen color: Close to 156A. Pistils: To date, pistil development on sterile flowers of the new *Hydrangea* has not been observed.

Reproductive organs, fertile flowers.—Stamens: Quantity per flower: About eight or nine. Filament length: About 2 mm to 5 mm. Filament color: Close to NN155A. Anther length: About 1 mm. Anther shape: Orbicular or parted. Anther color: Close to 159D. Pollen amount: Abundant. Pollen color: Close to 156A. Pistils: Pistil quantity per flower: Typically three. Pistil length: About 3 mm. Stigma shape: Rounded. Stigma color: Close to NN155C. Style length: About 2.5 mm. Style color: Close to 154C. Ovary color: Close to 154C.

Seeds.—To date, seed production has not been observed on plants of the new *Hydrangea*.

Pathogen & pest resistance: To date, under commercial production conditions, plants of the new *Hydrangea* have not been observed to be resistant to pathogens and pests common to *Hydrangea* plants.

Garden performance: Plants of the new *Hydrangea* have been observed have good garden performance and to be suitable for USDA Hardiness Zones 5 through 9.

It is claimed:

1. A new and distinct *Hydrangea* plant named 'LC NO5' as illustrated and described.
